VALVE HAVING SEAT-CARRYING FLANGE
John L. Williams, P.O. 162, Oswego, Oreg.
Filed Jan. 24, 1963, Ser. No. 254,045
4 Claims. (Cl. 251—328)

This invention relates to blade type gate valves and particularly to blade type gate valves having replaceable elastomer seats. This application includes the subject matter of my prior copending application entitled "Valve Having Seat-Carrying Flange," Serial No. 90,830, filed February 21, 1961, now abandoned, and is a continuation-in-part thereof.

There is an increasing demand for and it is a main object of the present invention to provide a low cost blade type gate valve having a removable elastomer seat.

A more specific object is to provide in a blade type gate valve in which the blade moves along a predetermined path, a removable flow passage member secured in a special manner in the body of the valve and having an elastomer seat which is specially formed so that it is not damaged because of the contact therewith of the fixed path blade.

A further object is to provide a wafer valve of the above type having a cast body.

Various other objects of the invention will be apparent from the following description taken in connection with the accompanying drawings wherein:

FIG. 1 is an elevational view of the outlet end of a valve of the present invention, parts being broken away to better show certain features of the valve;

FIG. 2 is a vertical midsection taken along line 2—2 of FIG. 1;

FIG. 2A is an enlarged view of the portion of FIG. 2 indicated by the arrow leading from FIG. 2A to FIG. 2;

FIG. 3 is a fragmentary end elevational view of a modified form of the invention;

FIG. 4 is a vertical sectional view taken along line 4—4 of FIG. 3;

FIG. 5 is an enlarged view of the designated portion of FIG. 4;

FIG. 6 is a fragmentary end elevational view of another form of the invention; and

FIG. 7 is a vertical sectional view taken along line 7—7 of FIG. 6.

Introductory Matter

Referring to the drawings, the valve shown has a flat wafer type body 11 formed with a flow passage extending therethrough with an axis at P. In FIG. 2, the inlet is to the right and the outlet to the left. The body is also formed with a gate blade channel 13 or guideway intersecting the flow passage. A gate blade 15 is movably received by the channel 13 and passes through an inverted packing gland 17 covered by my Patent Re. 24,735.

The blade is raised and lowered by means of a threaded stem 19 adjustably connected at 20 to the blade 15 and threadedly extending through a nut 21. The nut carries a handwheel 23 and is rotatably mounted on the upper end of a two legged frame 25 shown in my Patent Des. 179,791. The frame is bolted at 27 to the body 11.

An adjustable stop 29 is preferably provided on the upper end of the stem 19 to limit downward movement thereof. Turning the wheel 23 one way raises the blade 15 and turning it the other way lowers the blade.

Specific Consideration

The valve body 11 may be considered as comprising a cast flat wafer type main body portion 31 and a flow passage member 33. The main body portion is formed with a bore 35 (FIG. 2A) provided with threads which threadedly receive the flow passage member 33.

2

The flow passage member 33 includes a tubular portion 37 formed on its inner end with an annular axially facing channel receiving an annular elastomer seat 39. The seat has a rib 41 projecting beyond the flow passage members and being of rounded cross section for good sealing engagement with the blade 15.

The orientation of the seat 39 is determined by the tubular portion 37, but the location of the seat relative to the blade and main body portion is determined by 10 a radial flange 43 formed as an integral extension of the tubular portion 37. This flange engages a face 45 formed on the main body portion to limit inward threading movement of the flow passage member. The various 15 portions of the flow passage member are so dimensioned that when the flange 33 engages the face 45, the seat rib 41 projects into the path of movement of the blade 15 to form a good seal with the rib.

The blade 15 has a semicircular lower end (FIG. 1) which has a small bevel 46 (FIG. 2A) on the outlet end 20 so that the blade does not cut the seat 39. The bevel is exaggerated in the drawings so that it will be visible.

The blade 15 has a width equal or slightly greater than the outer diameter of the seat 39. Thus when the blade is closed, rib 41 engages margins of the blade at 25 the lower end of the blade.

The channel 13 has a width slightly greater than the width of the blade and extends downwardly slightly below the tubular portion 37 of the flow passage member as best shown in FIG. 2A. The inlet portion of the flow 30 passage is formed by a frusto-conical surface 71 defining a radially inwardly tapering face on the main body portion. The frusto-conical surface 71 merges into a short cylindrical portion 73 having the same diameter as the inside of the flow passage member 33.

The frusto-conical surface provides clearance for the blade channel, assuring that stock fibers will not be trapped and accumulated in the lower end of the channel. When the blade is open, the fluid flowing through the valve may readily wash any fibers away.

A pair of wedges 75, one of which is shown in FIGS. 1 and 2, is provided on the main body portion in position to engage the lower edge of the blade during the last increment of closing movement of the blade. In fact, the wedges engage a bevel 77 formed on the lower end 40 of the blade on the inlet side thereof and force the blade 15 over to assure better engagement of the blade with the seat 39. The bevel 77 is considerably greater than the bevel 46.

The flange 43 has its outer face machined for proper 50 engagement with the opposed face of a pipe flange 81 on a pipe 82. The main body portion 31 has chest walls 83 and thickened flange portions 84. The main body portion is also formed with a plurality of lugs 85 formed with threaded holes 86 to receive bolts, bolts 87 for the flange 81 being shown securing the pipe flange to the body. The main body portion is also formed with a heavy boss or rib 88 around the upper portion thereof on which is mounted the frame 25 and the bolts for the box 17. The body is also formed with a rib 89 fitting into the inverted box 17.

The main body portion is further formed with an annular face or seat 91 (FIG. 2A) obliquely related to the flow passage (shown at a 45 degree angle). An O-ring 93 fits around the tubular portion 37 of the flow passage member next to the flange 43 and is pressed by the flange against the face or seat 91 to form a fluid seal between the main body portions 31 and the flow passage member 33.

One or more gaskets may be used between the flange 43 and the face 45 to regulate the amount of projection of the rib 41 into the path of movement of the blade 17.

When the rib wears, removal of one or more gaskets would cause the rib to project farther toward the blade for proper contact.

An advantage of the valve is that either a circular or an oval opening (vertically elongate) may be cast in the flow passage member 33 to vary the capacity of the valve. The outside of the member would be circular in either case.

In a typical six-inch valve of the present invention, the rib 41 would be compressed approximately $\frac{1}{32}$ of an inch prior to engagement of the blade with the wedges 75, and approximately $\frac{1}{16}$ of an inch after such engagement.

A plurality of notches 101 or lugs, preferably four, is provided on the edge of the flange 43 to facilitate engagement by a tool when inserting or removing the flow passage member.

FIGS. 3, 4 and 5 show a modified form of the invention in which the valve body 11a comprises a main body portion 31a and a flow passage member 33a. The flow passage member has a tubular flow passage portion having a light press fit in a plain bore 35a which is formed in the body portion 31a.

The body portion 31a is formed with a recess 102 to accommodate the flange portion 43a of the member 33a. The depth of the recess 102 is such that the face-to-face dimension "a" (FIG. 4) of the valve is the same as a similar valve not so recessed and having two plain faces.

It follows from the above that I have provided a method of converting an existing plain face wafer valve to a wafer valve having a separable flange face without altering the face-to-face dimension of the valve. Thus a valve which is converted in accordance with my teachings can be replaced in the same installation from which it was removed, without requiring alterations in the installation to accommodate the converted valve.

The flow member 33a is held in place by three screws or bolts 103 which are equally distributed about the periphery of the member 33a. The peripheral margin of the flange portion 43a is provided with three dished recesses 105 to accommodate the heads of the screws 103.

I have discovered a novel way of installing the flow member 33a in the main body portion 31a. First, I locate the recesses 105 so that they are in approximate alignment with the side wall portions of the lugs 85a, and then the member 33a is pressed into place. Thereafter, the threaded holes for the screws 103 are provided in the lugs 85a in register with the recesses 105. Then the screws are threaded into place, and because of the recesses 105, the heads of the screws will be disposed inwardly of the outer face of the flange 43a. Thus, the heads of the screws do not interfere with the proper face-to-face contact between the flow member 33a and the flange of an adjacent pipe (not shown).

While an O-ring seal is not shown in FIGS. 3-5 for the member 33a, one is contemplated, if required. However, the press fit of the flow passage member within the main body portion 31a is sufficient in a number of installations to prevent leakage.

The tubular flow passage portion of the flow passage member 33a is provided on its inner end with an annular groove. A circular elastomer sealing member 39a has a body portion secured in the groove on member 33a and has a blade engaging portion 41a projecting into the path or plane of movement of the blade 15a to be engaged by said blade and be compressed by such engagement so as to form a seal with said blade.

The blade engaging portion 41a is of lesser width than the body portion of the sealing member 39a and is disposed intermediate the inner and outer edges of said body portion. Thus the blade engaging portion 41a is surrounded by a matrix of elastomer material so that said blade engaging portion can readily be deformed laterally without danger of rupturing it.

It is further pointed out that the blade engaging portion 41a is rounded or of convex semicircular form in cross

section for camming contact with the blade 15a. The blade has a slight bevel 46a for camming contact with the blade engaging portion 41a of said sealing member. Thus there is mutual camming contact between the blade 15a and the blade engaging portion 41a so that repeated engagement between said blade and sealing member will cause only a minimum wear on the latter despite the predetermined plane of movement of said blade.

The groove in the tubular flow passage portion is of dovetail form and the body portion of the sealing member is of regular trapezoidal form in cross section to fit in the groove and be retained in place.

FIGS. 6 and 7 show another modified form of the invention which is basically like the FIGS. 3-5 form, except that the flange portion 43b of the flow member 33b is formed with countersunk holes to receive and accommodate the screws 103b. The holes are drilled after the flow passage member is pressed into place.

The advantage of the FIGS. 3-5 form over the FIGS. 6 and 7 form is that there is less likelihood of leakage across the face of the flange portion 43a than across the flange portion 43b because the recesses 105 occupy less radial distance of the flange 43a than do the countersunk holes for the flange portion 43b.

While I have shown the concepts of my invention embodied in a wafer type gate blade valve, the concepts could be embodied in other gate blade valves, such as for instance a digester type gate blade valve.

Having described the invention in what is considered to be the preferred embodiment thereof, it is desired that it be understood that the invention is not to be limited other than by the provisions of the following claims.

I claim:

1. A valve comprising
a body having a flow passage intersecting a gate blade channel,
a gate blade movable in said channel between an opened and a closed position and projecting from said body, a packing assembly around said blade at the place it projects from said body and establishing a predetermined plane of movement for said blade,
said body including a main body portion and a removable flow passage member,
said flow passage member including a tubular flow passage portion,
said main body portion having a bore in which said tubular flow passage removably fits,
said tubular flow passage portion defining part of said flow passage,
said flow passage member including an annular flange portion bearing against said main body portion outwardly of said tubular flow passage portion,
threaded means for securing said flow passage member to said main body portion,
said tubular flow passage portion terminating short of the plane of movement of said blade,
said tubular flow passage portion having an annular groove formed on its inner end,
a circular elastomer sealing member having a body portion fitting in said groove and having a blade engaging portion projecting into the plane of movement of said blade to engage said blade and be compressed thereby to form a seal with said blade,
said blade engaging portion being of lesser width than the body portion of said sealing member and being disposed intermediate the inner and outer edges of such body portion so that said blade engaging portion is surrounded by a matrix of elastomer material so that said blade engaging portion can readily be deformed laterally without danger of rupturing it,
said portion being rounded for camming contact with said blade and said blade having a slight bevel on the edge thereof next to said sealing member for mutual camming contact with said rounded portion so that repeated engagements between said blade

and sealing member will cause only a minimum of wear on the latter despite the predetermined plane of movement of said blade.

2. A valve comprising
 a body having a flow passage intersecting a gate blade channel, 5
 a gate blade movable in said channel between an opened and a closed position and projecting from said body,
 a packing assembly around said blade at the place it projects from said body and establishing a predetermined plane of movement for said blade, 10
 said body including a main body portion and a removable flow passage member, 15
 said flow passage member including a tubular flow passage portion, 20
 said main body portion having a bore in which said tubular flow passage removably fits, 25
 said tubular flow passage portion defining part of said flow passage, 30
 said flow passage member including an annular flange portion bearing against said main body portion outwardly of said tubular flow passage portion, 35
 threaded means for securing said flow passage member to said main body portion, 40
 said tubular flow passage portion terminating short of the plane of movement of said blade, 45
 said tubular flow passage portion having an annular groove formed on its inner end, 50
 a circular elastomer sealing member having a body portion fitting in said groove and having a blade engaging portion projecting into the plane of movement of said blade to engage said blade and be compressed thereby to form a seal with said blade, 55
 said blade engaging portion being of lesser width than the body portion of said sealing member and being disposed intermediate the inner and outer edges of such body portion so that said blade engaging portion is surrounded by a matrix of elastomer material so that said blade engaging portion can readily be deformed laterally without danger of rupturing it, 60
 said portion being rounded for camming contact with said blade and said blade having a slight bevel on the edge thereof next to said sealing member for mutual camming contact with said rounded portion so that repeated engagements between said blade and sealing member will cause only a minimum of wear on the latter despite the predetermined plane of movement of said blade, 65
 said tubular flow passage portion and said flange portion defining a corner, 70
 an O-ring seal fitting around said tubular flow passage portion at said corner, 75
 said main body portion having an outward facing surface adjacent but in spaced relation to said corner and between which and said corner said O-ring is compressed in sealing engagement with said flow passage member and said main body portion.

3. A valve comprising
 a body having a flow passage intersecting a gate blade channel, 60
 a gate blade movable in said channel between an opened and a closed position and projecting from said body, 65
 a packing assembly around said blade at the place it projects from said body and establishing a predetermined plane of movement for said blade, 70
 said body including a main body portion and a removable flow passage member, 75
 said flow passage member including a tubular flow passage portion, 80
 said main body portion having a bore in which said tubular flow passage has a light press fit to form a seal with the walls of said bore, 85
 said tubular flow passage portion defining part of said flow passage, 90
 said flow passage member including an annular flange portion bearing against said main body portion outwardly of said tubular flow passage portion, 95
 threaded means for securing said flow passage member to said main body portion, 100
 said tubular flow passage portion terminating short of the plane of movement of said blade, 105
 said tubular flow passage portion having an annular groove formed on its inner end, 110
 a circular elastomer sealing member having a body portion fitting in said groove and having a blade engaging portion projecting into the plane of movement of said blade to engage said blade and be compressed thereby to form a seal with said blade, 115
 said blade engaging portion being of lesser width than the body portion of said sealing member and being

said tubular flow passage portion defining part of said flow passage, 120
 said flow passage member including an annular flange portion bearing against said main body portion outwardly of said tubular flow passage portion, 125
 threaded means for securing said flow passage member to said main body portion, 130
 said tubular flow passage portion terminating short of the plane of movement of said blade, 135
 said tubular flow passage portion having an annular groove formed on its inner end, 140
 a circular elastomer sealing member having a body portion fitting in said groove and having a blade engaging portion projecting into the plane of movement of said blade to engage said blade and be compressed thereby to form a seal with said blade, 145
 said blade engaging portion being of lesser width than the body portion of said sealing member and being disposed intermediate the inner and outer edges of such body portion so that said blade engaging portion is surrounded by a matrix of elastomer material so that said blade engaging portion can readily be deformed laterally without danger of rupturing it, 150
 said portion being rounded for camming contact with said blade and said blade having a slight bevel on the edge thereof next to said sealing member for mutual camming contact with said rounded portion so that repeated engagements between said blade and sealing member will cause only a minimum of wear on the latter despite the predetermined plane of movement of said blade, 155
 said threaded means comprising a plurality of threaded elements, 160
 said main body portion having threaded holes receiving said threaded elements, 165
 said elements having heads engaging said flange portion, 170
 said flange portion being recessed to accommodate said heads so that the outer surfaces of said heads are disposed inwardly of the outer face of said flange portion, 175

4. A valve comprising
 a body having a flow passage intersecting a gate blade channel, 180
 a gate blade movable in said channel between an opened and a closed position and projecting from said body, 185
 a packing assembly around said blade at the place it projects from said body and establishing a predetermined plane of movement for said blade, 190
 said body including a main body portion and a removable flow passage member, 195
 said flow passage member including a tubular flow passage portion, 200
 said main body portion having a bore in which said tubular flow passage has a light press fit to form a seal with the walls of said bore, 205
 said tubular flow passage portion defining part of said flow passage, 210
 said flow passage member including an annular flange portion bearing against said main body portion outwardly of said tubular flow passage portion, 215
 threaded means for securing said flow passage member to said main body portion, 220
 said tubular flow passage portion terminating short of the plane of movement of said blade, 225
 said tubular flow passage portion having an annular groove formed on its inner end, 230
 a circular elastomer sealing member having a body portion fitting in said groove and having a blade engaging portion projecting into the plane of movement of said blade to engage said blade and be compressed thereby to form a seal with said blade, 235
 said blade engaging portion being of lesser width than the body portion of said sealing member and being

disposed intermediate the inner and outer edges of such body portion so that said blade engaging portion is surrounded by a matrix of elastomer material so that said blade engaging portion can readily be deformed laterally without danger of rupturing it, said portion being rounded for camming contact with said blade and said blade having a slight bevel on the edge thereof next to said sealing member for mutual camming contact with said rounded portion so that repeated engagements between said blade and sealing member will cause only a minimum of wear on the latter despite the predetermined plane of movement of said blade,

10 said threaded means comprising a plurality of threaded elements,

15 said main body portion having threaded holes receiving said threaded elements,

8

said elements having heads engaging said flange portion,

said flange portion being recessed to accommodate said heads so that the outer surfaces of said heads are disposed inwardly of the outer face of said flange portion,

the shank portions of said threaded elements being disposed outwardly of the peripheral edge of said flange portion.
